(57) **CLAIM**

The ornamental design for wearable key fob clip, as shown and described.

DESCRIPTION

FIG. 1 is an perspective view illustrating a embodiment of a wearable key fob clip of the claimed design;

FIG. 2 is an front view of the wearable key fob clip shown in FIG. 1;

FIG. 3 is a back view of the wearable key fob clip shown in FIG. 1;

FIG. 4 is a right view of the wearable key fob clip shown in FIG. 1;

FIG. 5 is a left view of the wearable key fob clip shown in FIG. 1;

FIG. 6 is a top view of the wearable key fob clip shown in FIG. 1; and,

FIG. 7 is a bottom view of the wearable key fob clip shown in FIG. 1.

The broken line showing of dual ovals in FIGS. 1 and 6 is included for the purpose of illustrating non-claimed environmental matter and forms no part of the claimed design.

1 Claim, 7 Drawing Sheets

FIG. 4

FIG. 5

{

FIG. 6

A curly brace is positioned below the bag, indicating its depth or thickness.

FIG. 7
